UNITED STATES PATENT OFFICE.

JOHN PFEIFER, OF SPRINGFIELD, OHIO, ASSIGNOR OF ONE-THIRD TO
F. R. BURTON, OF SPRINGFIELD, OHIO.

WRAPPING-MACHINE.

No. 821,375.

Specification of Letters Patent.

Patented May 22, 1906.

Application filed May 28, 1904. Serial No. 210,212.

To all whom it may concern:

Be it known that I, JOHN PFEIFER, a citizen of the United States, residing at Springfield, in the county of Clark and State of Ohio, have invented certain new and useful Improvements in Wrapping-Machines, of which the following is a specification.

My invention relates to automatic package-wrapping machines, and especially to that class of wrapping-machines whereby the package-cover is secured by twisting the ends.

The device hereinafter described is especially adapted for wrapping small pieces of candy each in a separate paper wrapper and securing the same by twisting the ends. However, by modifying the proportions of the various parts the mechanism herein shown may be adapted to operate on various articles of various sizes, including different kinds of fruit, &c.

The object of my invention is to greatly simplify the construction, as well as the means and modes of operation, of such machines, whereby they are not only cheapened, but are rendered unlikely to get out of order and are made easy of operation.

With the above primary and other incidental objects in view the invention consists of the means, mechanism, construction, and mode of operation hereinafter described, and set forth in the claims.

In the drawings, Figure 1 is a front elevation of the machine, showing the side from which the candy is fed. Fig. 2 is a rear elevation or view of the side opposite that shown in Fig. 1. Fig. 3 is a sectional elevation on line $x-x$ of Fig. 2 viewed as indicated by the arrows. Figs. 4 and 5 relate to the paper-feeding devices. Fig. 6 shows the paper-cutting knife with cam for operating same, which cam also operates the candy-cutting knife. Figs. 7 and 8 illustrate the wrapping and twisting mechanism and cams for operating same. Fig. 9 is a view of the mangle-gears for transmitting an intermittent movement to the wrapping and twisting mechanism. Figs. 10, 10^a, 10^b, 10^c, and 10^d are end views of the wrapping and twisting mechanism, showing in regular sequence the various positions assumed by the gripping-fingers during the operation. Figs. 11 and 12 relate to the candy-holding devices. Figs. 13, 14, and 15 show the candy-package in various stages of completion.

Like parts are indicated by similar characters of reference throughout the several views.

A represents the base, on which are mounted the upright end frames A'. These frames are connected at the top by the rod A², on the front side by the longitudinal bars A³ and A⁴, and on the rear side by the bar a. Extending longitudinally through the machine and having bearings in said upright frames is the main operating-shaft, (indicated by the numeral 1.) The shaft 1 carries a series of cams and gears, which actuate the various movable parts of the machine at the proper times.

Paper-feeding mechanism.—The paper from which the wrappers are to be formed is provided in a continuous web a', which is pivotally supported upon an upright member a⁵, having an adjustable collar a⁶ for the support of the web. An L-shaped arm extends laterally from said collar a⁶ and carries at its extremity a spring-pressed plate a⁷, forming a tension device on the paper web. Adjustably attached to a pendent arm a⁸ of the bar a is a "friction-plate" a⁹, Figs. 2 and 4, which cooperates with a vertical plate a¹⁰ to retain in proper position for the next operation the end of the paper web after the portion necessary to form a wrapper has been severed. These plates a⁹ and a¹⁰ also form a guide and support for the paper while being cut, as hereinafter described.

Movably mounted on the bar a is a head a¹¹, (see Figs. 2 and 5,) carrying L-shaped paper-pulling jaws. One of these pulling-jaws a¹² is formed rigid with the head a¹¹, the other pulling-jaw a¹³ being mounted in suitable bearings on said head and provided with a spring a¹⁴, which normally presses the extremity of the jaw a¹³ into contact with that of a¹². The pulling-jaw a¹³ has a rearwardly-extending arm a¹⁵, in proximity to which is a pivoted spring-actuated trigger a¹⁶, which is adapted to engage the arm a¹⁵ and hold the jaws a¹² and a¹³ apart against the tension of the spring a¹⁴. As shown in Fig. 5, the arm a¹⁵ is preferably formed flat, with a rectangular notch a¹⁷ in its lower edge, and the trigger a¹⁶ is provided with a shoulder near its inner end to engage in said rectangular notch. There is also pivoted to the head a¹¹ a bell-crank lever a¹⁸, one end of which normally contacts with the extremity of the arm a¹⁵ and the other extends laterally into the path of an adjustable stop

a^{16} , mounted on the bar a . The head a^8 is caused to slide forward and back on the bar a by means of a link a^{17} and a pivoted arm a^{18} , which is spring-actuated in one direction by 5 a spring a^{19} . The movement of the arm a^{18} , and thereby the head a^8 , is regulated by a face-cam a^{20} , carried on the end of the main shaft 1, Figs. 1 and 2.

Referring to Fig. 1, as the cam a^{20} rotates, 10 as indicated by the arrows, under the influence of power applied to the driving-wheel 2 at the opposite end of the shaft 1 the pivoted arm a^{18} , carrying with it the head a^8 , will move inwardly as the roller a^{21} travels over the inclined portion a^{22} of the cam a^{20} . At 15 the time the roller a^{21} drops off the extremity of the inclined cam portion a^{22} the head a^8 has approached the end of the paper web. As the said roller drops from the incline the 20 head is suddenly advanced. The trigger a^{13} contacts with an adjustable stop a^{23} , which disengages said trigger from the arm a^{12} and allows the jaws a^9 a^{10} to close upon the end of the paper web, which they do by extending 25 into a rectangular notch a^{24} in the plates a^9 and a^7 . The object of the sudden drop off at the extremity of the inclined cam portion a^{22} is to give to the head a^8 sufficient momentum to trip the trigger a^{13} . This might also 30 be accomplished by increasing the tension of the spring a^{19} , but would require additional power to overcome this spring in returning the parts to normal position. Therefore the first method is preferable. The pulling-jaws 35 having thus engaged the end of the paper web, the cam a^{20} in its continued movement will cause the head a^8 to travel back as the roller a^{21} travels over the inclined portion a^{22} until it reaches the "dead" portion a^{26} , when 40 the head a^8 will for a moment remain at rest, with the outer end of the bell-crank lever a^{15} in contact with the stop a^{16} . During the 45 backward movement of the head a^8 sufficient paper will have been pulled from the web to form one wrapper. While the head a^8 remains at rest, as before mentioned, the length of paper is severed from the web by a 50 stroke of the paper-knife b , Figs. 2, 3, 4, and 6.

Paper-cutting mechanism.—The paper-knife b is pivoted on a longitudinal shaft 3. To a downwardly-projecting arm b' there is attached a spring b^1 , adapted to throw the knife forcibly against the paper when so permitted by the cam b^3 , over the periphery of 55 which the roller b^4 travels. The blade of the knife b is formed with two cutting edges b^5 b^6 , arranged angularly to each other. By this arrangement the paper is severed by being punctured near the center by the apex b^7 and 60 then cut in both directions to its edges. The friction-plate a^9 forms a support for the paper while being cut, and in order that the paper may be properly supported at the rectangular notch where it would otherwise tear there 65 is provided a supplementary pivoted support

b^8 , hinged on the bar A^3 and normally held in the position shown in Fig. 4 by the spring b^9 , the movement in one direction being limited by the contact of the stop-arm b^{10} with the bar A^3 . The support b^8 is further supplied with a lateral arm b^{11} , adapted to be contacted by the head a^8 , whereby the said support will be moved from the path of the pulling-jaws a^9 a^{10} at the proper time. After the paper has thus been severed the raised portion 70 a^{26} of the cam a^{20} in its movement will release the pulling-jaws from the paper by giving to the head a^8 an additional movement, whereby the outer extremity of the bell-crank lever a^{15} will contact with the stop a^{16} and be turned 75 about its pivotal point, and the inner end of said lever pressing on the lever a^{12} will open the pulling-jaws until the lever a^{12} is engaged by the trigger a^{13} . When thus disengaged from the feeding devices, the paper will be 80 held between a pressure-arm c' and a tympan-plate c , Figs. 1, 2, and 3, pivotally attached to the longitudinal rod A' and provided with a spring c' , which tends to throw the tympan-plate c into proximity with the path of the 85 paper while being pulled from the web, the movement in this direction being limited by the contact of the arm c^2 with a stop c^3 on the inner side of the bar A^3 . The pressure-arm c' is pivoted on the shaft 3 and is actuated by 90 a spring c^6 , the movement being regulated by a cam c^6 on the operating-shaft 1. Said pressure-arm c' is provided with a pivoted head c^7 of a length substantially equal to the width of the tympan-plate c . The object of pivotally connecting the head c^7 is to make the 95 same self-adjustable, so that the pressure at both ends may be equal. As the pressure-arm c' moves inwardly under the influence of the spring c^6 and cam c^6 it carries the severed portion of the paper with it, forcing the tympan-plate about its pivotal points until it contacts with the wrapping and twisting mechanism, and the paper is now in position 100 to be operated upon.

Wrapping and twisting mechanism.—There are two sets of wrapping and twisting mechanism extending inwardly from the upright frame A' and above the shaft 1, and as the two sets are identical in construction and operation only one will be described, which description will apply equally to the other. It must be understood, however, that the relations of the parts are reversed, the sets of mechanism being arranged right and left 105 handed.

Referring to Sheet 4 of the drawings and particularly to Fig. 7, the wrapping and twisting mechanism is mounted on a splined shaft e , having a bearing in the upright frame A' 110 and a second bearing outside said frame A' , preferably in a bracket e' , extending therefrom; but this second bearing might be in an entirely separate upright frame. At the inner end the shaft e carries a cylindrical 115

head e^2 , preferably having a rubber covering e^3 . In proximity to this head e^2 there is rigidly secured to the shaft e a disk e^4 , having on the side toward said head a projecting hub e^5 . Slidably mounted on the shaft e , but adapted to rotate therewith by means of engagements with the spline of said shaft, are two disks e^6 and e^7 . To provide better bearing, these disks are equipped with sleeves e^8 and e^9 .

Attached to the disk e^6 and extending through openings in the disks e^6 and e^7 are two small rods e^{10} , having L-shaped gripping-fingers e^{11} at their extremities having pivotal connections with said rods e^{10} , located in the angle of said L-shaped fingers. Attached to the disk e^7 and extending through the disk e^7 is a rod e^{12} , having a finger e^{13} in all respects like those before mentioned. Attached to each of the rods e^{10} and e^{12} , respectively, and to the disk e^7 are springs e^{14} , which tend to pull said rods, with their connections, inwardly toward the heads e^2 . When thus moved inwardly, the short arms of the L-shaped gripping members contact with the face of the head e^2 , and the said gripping-fingers are turned on their pivotal connections until the longer arm of said fingers is pressed tightly on the periphery of said head e^2 , as is shown the finger e^{13} of Figs. 2 and 7. The tendency of the fingers to close under the influence of the springs e^{14} is resisted until the proper moment by the levers e^{15} and e^{16} , pivotally secured to the bar A^4 . For convenience of adjustment said levers are secured through a slotted opening e^{17} in said bar A^4 . These levers e^{15} and e^{16} are controlled by cams d and d' on the shaft 1 and are provided at their lower ends with rollers e^{18} and e^{19} , which travel over the face of said cams. At the upper end the lever e^{15} has a roller e^{20} , engaging the inner face of the disk e^6 , and the lever e^{16} is provided with a bifurcated stud e^{21} , straddling the edge of the disk e^6 , thereby causing the disk e^6 to be moved in either direction by the movement of the lever e^{16} . The tendency of this disk e^6 to move inwardly or in opposition to the cam d' is increased by a spring e^{22} , attached at one end to the lever e^{16} and at the other to the bar A^4 , Fig. 1.

An intermittent movement is transmitted to the shaft e from the main shaft 1 by peculiarly-constructed gears, as illustrated in Fig. 9. The larger gear f on the main operating-shaft is a mangled face-gear having a projecting face f' , the radius of which corresponds to the radius of the sides f^2 of the small gear f^3 , which is splined on the shaft e . The contact of the convex periphery of the projecting face f' of the large gear with the concave face f^2 of the small gear prevents the latter from turning except when moved by the pins or teeth of the face-gear. In this respect the construction of these gears is quite similar to what is technically known as

the "Geneva-stop" movement of watch and clock construction.

When the section of paper g , Fig. 2, destined to form the wrapper, is pressed against the heads e^2 by the pressure-arm c^4 , the relative position of the gears f and f^3 is as shown in Fig. 9 and that of the gripping-fingers each extended, as in Fig. 10. At this moment the rollers e^{18} and e^{19} of the levers e^{15} and e^{16} have reached the summit of the inclines d^a and d^b of the cams d and d' , respectively, thus forcing the disks e^6 and e^7 , with their attached rods and gripping-fingers, to their extreme outward position, in which the short arms of the gripping-fingers e^{11} and e^{13} contact the hub e^5 of the disk e^4 , and the fingers are turned on their pivotal points to their extreme open position, Fig. 10. In the continued rotation of the cams d and d' with the shaft 1 the roller e^{18} of the lever e^{15} drops over the shoulder d^4 of the cam d , which allows the disk e^6 to move inwardly under the influence of the spring e^{14} , and the finger closes on the lower portion of the paper g , as shown in Fig. 10^a. The shaft 1, with the gear f , rotates as indicated by the arrow, and the group f^4 of two teeth or pins on the face-gear f engages the gear f^3 and gives to it and the connected mechanism a half-revolution, which brings the paper and fingers to the position shown in Fig. 10^b, where they again come to rest. The paper being in the form of a semi-circular trough is in position to receive the candy, which is deposited as hereinafter described. (See Fig. 13.)

After the deposit of the candy the group f^6 of teeth of the gear f engage the gear f^3 and give to it and the wrapping mechanism a complete rotation, which carries the parts to the position indicated in Fig. 10^c, the paper being in a straight tubular form g' , Fig. 14, with the candy inclosed. At this time the roller e^{19} of the lever e^{16} passes over the offset d^5 of the cam d' , which permits the disk e^6 , with its attached rods and fingers, to move inwardly under the influence of their respective springs e^{14} , and the fingers e^{11} are caused to grip the paper, as shown in Fig. 10^d. The package is now ready for the twisting of the ends; but as both sets of the wrapping and twisting mechanism rotate in the same direction it is necessary to hold the candy within the package stationary during the operation.

Holding mechanism.—The holding mechanism is indicated in Figs. 1 and 3 and in detail in Figs. 11 and 12. The lower clamping member i is provided with an inclined head i' , having a depression therein of slightly greater radius than the article to be wrapped. There is also provided a slot i^2 in the member i , engaging the shaft 1, and an extended leg i^3 , having a guide i^4 , located on the base A . The lower clamping member i is capable of only a vertical movement and is actuated by a cam i^5 on the shaft 1 engaging with a roller i^6 .

*i*⁶ on said member *i*. The upper clamping member has a compound movement, its line of travel being similar to the outline of a parallelogram. It consists of a shaft *h*, bent into a U form, Figs. 1 and 11; one leg having a bearing on a plate *h'*, attached to the bar *A*⁴. At its upper portion this plate is extended horizontally rearward, forming a table *h'*, upturned at the end, which is slotted to permit the passage of the head *i'* of the lower clamping member *i*. A spring *h*⁸, coiled about the lower leg of the U-shaft *h*, tends to throw said U-shaft forward or away from the bar *A*⁴, which movement is resisted by the action of a cam *h*⁴, mounted on the shaft 1 and acting on a rearwardly-extending arm *h*⁵, attached to the lower leg of said U-shaped shaft. Pivotally connected to the upper leg of said U-shaped shaft *h* is a plate *h*⁶, having an extended arm terminating in an arched portion *h*⁷, of somewhat greater radius than the average article to be wrapped. A spring *h*⁸ tends to move this plate *h*⁶ downwardly about its pivotal connection, which movement is opposed by the cam *h*⁹ and link *h*¹⁰. The link *h*¹⁰ is pivotally connected with the plate *h*⁶. Its opposite end is bifurcated and straddles the shaft 1. A roller *h*¹¹ on the side of said link travels over the periphery of the cam *h*⁹, the action of the cam being to force the plate *h*⁶ upwardly against the tension of the spring *h*⁸.

During the time the paper is being formed, as in Fig. 10^b, the roller of the arm *h*⁵ is traveling over the lowest or most central portion of the cam *h*⁴, and the U-shaft *h* has been turned about its pivotal connection through the influence of the spring *h*⁸ until it is in its extreme outward position, as shown in dotted lines in Fig. 12. At this time the roller *h*¹¹ of the link *h*¹⁰ travels onto a higher portion of the cam *h*⁹, and the pivoted plate *h*⁶ is forced upwardly against the tension of the spring *h*⁸, as in dot-and-dash lines of Fig. 12. As the arm *h*⁵ travels toward the higher portion of the cam *h*⁴ the U-shaft *h* moves rearwardly or toward the bar *A*⁴ until the plate *h*⁶ assumes the position shown in broken lines in Fig. 12. During this rearward movement the candy or other article to be wrapped is deposited in the paper, as will hereinafter be described. At this time the wrapping mechanism is given the complete rotation before mentioned, forming the paper as in Fig. 14. The roller *i*⁶ of the lower clamping member *i* has traveled during this rotary movement from the lower to the higher portion of the cam *i*⁸ and the head *i'* of the member *i* has been brought into contact with the under side of the package. The roller *h*¹¹ of the link *h*¹⁰ suddenly drops over the point *h*¹² of the cam *h*⁹, and the plate *h*⁶ moves downwardly with the arched portion *h*⁷ over the package, which is securely held between said arched portion

*h*⁷ and the head *i'* of the member *i*, as shown in full lines in Fig. 12.

The group *f*⁶ of six teeth on the gear *f* now engages the gear *f*³ and gives to the wrapping mechanism a revolution and a half, which results in the twisting of the ends of the package, since the center of the package is held stationary by the clamping devices before mentioned. As the twisting operation is accomplished the package is shortened in length, and to accommodate this the wrapping and twisting devices are permitted to move inwardly under the influence of the springs *e*²² by the rollers *e*¹⁹ of the levers *e*¹⁸ passing over the offset *d*⁶ onto the lowest portions of the cams *d*⁴. As the rollers *e*¹⁸ and *e*¹⁹ of the levers *e*¹⁵ and *e*¹⁶ reach the inclines *d*² and *d*³ of the cams *d* and *d*⁴, which they do simultaneously, the wrapping and twisting mechanism is returned to normal position. The short arms of the fingers *e*¹¹ and *e*¹³ contacting with the hub *e*⁴, the gripping-fingers release the ends of the package, the lower clamping member drops away from the package, the U-shaped shaft *h* at the same time turns about its pivotal connection to the extreme outward position under influence of the spring *h*⁸, and the wrapped package is ejected from the machine.

It is obvious that the wrapping mechanism can be so modified as to employ various amounts of paper, as by adding two teeth to the group *f*⁶ the wrapper instead of being extended once and a half around the article would be extended twice around, giving a double thickness. In a similar manner the number of twists given to the ends of the package may be modified, as by adding two teeth to the group *f*⁶ instead of a twist and a half two complete twists can be given to each end. It is to be noted that both ends of the package are twisted in the same direction, Fig. 15 showing the completed package with both ends twisted away from the observer.

It is further to be noted that the forming, wrapping, and twisting operations are all accomplished by the same set of mechanism.

Article-feeding mechanism.—In Figs. 1, 3, and 12 there is shown for the reception of the articles to be wrapped a chute or hopper *j* terminating substantially over the semicircular paper-trough formed preparatory to the depositing of the article therein. The lower end of this hopper *j* is slotted at *j'* (see Fig. 1) and provided with a spring-actuated gate *j*². Formed on the top of the arched portion *h*⁷ of the plate *h*⁶ is an upwardly-extending finger *j*³. During the outward or forward movement of the U-shaft *h* the plate *h*⁶ is in its depressed position, as shown in dotted lines in Fig. 12, and the finger *j*³ passes under the hopper *j*. However, when at the limit of the movement of the U-shaft *h* the plate *h*⁶ is

forced upwardly by action of the link h^{10} and cam h^9 , the finger j^3 enters the slot j' behind the lowermost article in the hopper j , as shown by dot-and-dash lines in Fig. 12. 5 During the forward movement of the U-frame the finger j^3 pushes the lowest article from the hopper against the resistance of the gate j^2 , which immediately springs back and closes the hopper j against the escape of the 10 next lowest article, the article ejected from the hopper meanwhile having dropped into the semicircular paper-trough previously prepared, as hereinbefore mentioned.

The mechanism thus far described may be 15 used for wrapping various articles, fruit, and pieces of candy which have previously been formed and cut to the proper shape and length. In addition to this there is shown in Figs. 1 and 3 mechanism for operating upon 20 candy in a mass by rolling it to proper shape, cutting it into predetermined lengths, and delivering it into the hopper j .

Candy forming and cutting devices.—This mechanism consists of a pair of corrugated 25 grooved rolls $k k'$, located at the end of a platen k^2 , Figs. 1 and 3. The rolls $k k'$ have intermeshing gears $k^3 k^4$. Said rolls $k k'$ are driven from the main shaft 1, as follows: Mounted on the shaft of one of said rolls, preferably 30 the lower, k' , is a bevel-gear k^5 , meshing with a similar gear on an inclined shaft k^6 , carrying a second bevel-gear at its opposite end, which meshes with a bevel-gear k^7 on a lateral shaft k^8 , which in turn carries a bevel-gear k^9 , 35 meshing with a gear k^{10} on the shaft 1. Immediately in front of the rolls $k k'$ is located a die-plate p , through openings $p' p^2$ of which the candy is discharged from the rolls $k k'$. The die-plate p forms a support for the candy 40 while being severed by the knife p^3 , which is pivoted on a supplementary upright frame L , which also provides bearings for the rolls $k k'$. There is also pivoted to the upright frame L an arm p^4 , carrying at its rearward end a 45 roller p^5 , which travels on the periphery of the cam b^2 . (See Fig. 6.) A link p^6 connects the arm p^4 and the knife p^3 , and a spring p^7 , between the arm p^4 and the base A , causes the knife to forcibly strike and sever the portion 50 of candy extending through the die-plate when the roller of the arm p^4 slips over the point b^{11} of the cam b^2 . An inclined chute p^8 carries the severed piece of candy to the hopper j , where it is operated upon, as 55 before described.

In order that the rolls $k k'$ may be driven intermittently, so that the candy shall not be forced through the die-plate until the knife p has been returned to its normal position out of the path of said candy, one of the bevel-gears in the train transmitting power from the shaft 1 to said rolls is mangled or formed with only a partial quota of teeth, as shown on the gear k^7 .

55 It will thus be seen that I have provided

for the purpose mentioned a machine simple and efficient in operation and one not only simple in construction, but provided with means for easy adjustment in assembling and compensating for wear on the parts.

Having thus described my invention, I claim—

1. In a machine as described, the combination with article-feeding mechanism, of wrapper-feeding mechanism, article-wrapping and wrapper-twisting devices, article-holding devices, and means for intermittently rotating said wrapping and twisting devices in the same direction, substantially as specified. 75

2. In a machine as described, the combination with wrapper and article feeding mechanism, of revoluble article-wrapping mechanism arranged in duplicate, means for holding the inclosed article against rotation during a portion of the period of rotation of said article-wrapping devices, and means for twisting the ends of the wrapper on opposite sides of the article being wrapped by the continuous rotation of the article-wrapping devices, substantially as specified. 80

3. In a machine as described, the combination with wrapper-feeding mechanism, of wrapper-gripping fingers, means for giving to said wrapper-gripping fingers a partial rotation, whereby the wrapper will be formed in a trough for the reception of the article to be wrapped, article-feeding mechanism, whereby the article will be deposited in said trough, means for giving to said wrapper-gripping fingers additional rotation, and holding means whereby the inclosed article will be held stationary while the wrapper-gripping fingers continue to rotate the ends of the wrapper, substantially as specified. 95

4. In a machine as described, wrapper-feeding mechanism, wrapper-gripping devices, means for giving to said wrapper-gripping devices a partial rotation, whereby said wrapper will be given a substantial U or trough shape, article-feeding mechanism, means for continuing the rotation of said wrapper-gripping devices, whereby the edges of the wrapper are closed about the article, and means for holding the wrapped article stationary while the wrapper-gripping devices continue to rotate, thereby twisting the ends of said wrapper, substantially as specified. 105

5. In a machine as described, the combination with article-feeding mechanism, of wrapper-gripping means, actuating means for moving said wrapper-gripping devices to form of said wrapper a pocket for the reception of the article, means for closing the opposite edges of the wrapper over said article, clamping devices adapted to hold said article against rotation, and twisting devices for twisting the opposite ends of said wrapper, substantially as specified. 110

6. In a machine as described, the combination with article feeding and wrapping mech- 130

anism, of a reciprocating head, wrapper-gripping jaws located on said head, means for opening and closing said jaws at predetermined points, a cam, connections between 5 said cam and reciprocating head, oppositely-disposed inclined faces on said cam, a "drop-off" terminating one of said inclined faces, and a "dead space" on the other inclined face, substantially as and for the purpose 10 specified.

7. In a machine as described, the combination with article feeding and wrapping devices, of a reciprocating head, wrapper-gripping jaws on said head, means for giving to 15 said head a sudden forward movement near the forward end of its stroke, and means for momentarily retarding the movement of said head during its rearward stroke, substantially as and for the purpose specified.

20 8. In a machine as described, the combination with article and wrapper feeding mechanism and article - wrapping mechanism, of a support for the web of wrapper material, a "friction-plate" adapted to maintain 25 the end of the wrapper material in position for engagement by the feeding mechanism, a wrapper-cutting knife, and a hinged support coöperating with said friction-plate to support the wrapper material during the 30 severing process, substantially as and for the purpose specified.

9. In a machine as described, the combination with article feeding and wrapping mechanism and wrapper feeding and severing 35 mechanism, of a tympan-plate, a pressure-arm, and a pivoted head on said pressure-arm, whereby the severed wrapper may be moved to position to be engaged by said wrapping mechanism, and so held under 40 even tension, substantially as and for the purpose specified.

10. In a machine as described, the combination with wrapper and article feeding mechanism, of wrapping and twisting mechanism arranged in duplicate, actuating 45 means for intermittently rotating said wrapping and twisting mechanism and means for preventing a revolute movement of said wrapping and twisting mechanism except 50 when actuated by said actuating means, substantially as and for the purpose specified.

11. In a machine as described, the combination with wrapper-feeding devices, of article wrapping and twisting devices consisting 55 of a longitudinally-movable shaft, a head on said shaft, gripping-fingers coöperating with said head to engage the ends of the wrapper, means to give to said wrapping and twisting devices substantially a half-rotation, 60 whereby the wrapper will be formed into a trough for the reception of the article to be wrapped, means for continuing the rotation of said wrapping and twisting devices after the deposit of said article, and holding devices whereby the said article and adjacent 65

portions of the wrapper will be held stationary during a portion of the continued rotary movement, substantially as specified.

12. In a machine for the purpose described, article feeding and wrapping and twisting mechanism consisting of a longitudinally-movable revolute shaft, a head on said shaft, rods arranged parallel with said shaft and slidably connected therewith, wrapper-gripping fingers provided with lateral arms pivoted to said rods, projections on said shaft adapted to be contacted by the lateral arms of said gripping-fingers when said rods are moved longitudinally, whereby said gripping-fingers will be moved about their 75 pivotal connections, substantially as and for the purpose specified.

13. In a machine as described, article feeding and wrapping devices, consisting of a revolute shaft, a head therein, pivoted gripping-fingers, sliding connections between said gripping-fingers and said revolute shaft, and means for longitudinally moving said fingers, whereby when moved in one direction they will engage said head, and when moved in the opposite direction they will be disengaged from said head, substantially as and for the purpose specified.

14. In a machine for the purpose mentioned, article feeding and wrapping and twisting mechanism comprising a revolute shaft, slideable members on said shaft, a head, and a hub carried by said shaft, parallel rods connected with said slideable members, wrapper-gripping fingers pivotally connected with 100 said rods, and means for moving said slideable member whereby the fingers contact with said head and hub respectively when moved in opposite directions and are thereby moved about their pivotal points, substantially as 105 and for the purpose specified.

15. In a machine as described, the combination of wrapper-feeding mechanism, means for feeding an article to be wrapped, and means for forming the wrapper into a 110 casing about said article and open at opposite ends, holding means for the article to be wrapped, and means for moving into operative position said holding means during a portion of the rotation of said wrapping 115 means, whereby the opposite ends of said wrapper will be twisted, substantially as specified.

16. In a machine as described, article feeding and wrapping mechanism consisting of a 120 revolute shaft, a head thereon, wrapper-gripping fingers adjacent thereto and adapted when moved longitudinally to coöperate with said head in engaging the wrapper, operating-cams, pivoted levers coöperating with 125 said cams to longitudinally move said fingers, and means for intermittently rotating said revolute shaft, substantially as specified.

17. In a machine as described, article feeding, and wrapping mechanism consisting of a 130

- longitudinally - movable revolute shaft, a head thereon, wrapper-gripping fingers adjacent thereto and arranged in sets, means for separately operating said sets of gripping-fingers and for intermittently rotating said revolute shaft, substantially as specified.
18. In a machine as described, article-wrapping mechanism consisting of a shaft, a head thereon, wrapper-gripping fingers located adjacent thereto, means for moving said wrapper-gripping fingers to cause their impingement on said head, and means for rotating said head and fingers, substantially as and for the purpose specified.
19. In a machine as described, the combination of means for feeding an article to be wrapped, wrapping and wrapper-twisting mechanism arranged in duplicate and on opposite sides of the article to be wrapped, article-clamping devices intermediate of said wrapping and twisting mechanism, said clamping devices being normally out of engagement with the article during the feeding and wrapping processes, and actuating means for said clamping devices whereby they will be caused to engage the article and hold same against rotation while the ends of the wrapper are being twisted, substantially as specified.
20. In a machine as described, means for feeding an article to be wrapped, of wrapping mechanism, twisting mechanism, means for holding stationary the article and the portion of wrapper immediately surrounding same while the ends of the wrapper are rotated both in the same direction, substantially as and for the purpose specified.
21. In a machine as described, the combination with article-feeding mechanism, wrapping and wrapper-twisting mechanism arranged in duplicate and on opposite sides of the article to be wrapped, article-clamping devices to engage said article after the completion of the wrapping process, actuating means for said clamping devices, and actuating means for said wrapping and wrapper-twisting mechanism, substantially as described.
22. In a machine as described, means for feeding an article to be wrapped, wrapping mechanism, a vertical-movable article-clamping member and a pivoted article-clamping member co-operating with said first-named clamping member to hold the article against rotation, and normally offset in its relation to said first-named clamping member, actuating means for said clamping members, and means for moving said pivoted clamping member laterally out of registry with said vertically-movable clamping member, substantially as specified.
23. In a machine as described, means for feeding an article to be wrapped, of wrapping mechanism, a vertical - movable clamping member, a pivoted spring-actuated clamping member co-operating with said first-named clamping member, and a pivoted spring-actuated support for said pivoted spring-actuated clamping member, and means to cause such members to engage the article, whereby the article will be held against rotation, substantially as and for the purpose specified.
24. In a machine as described, means for feeding an article to be wrapped, of wrapping mechanism, a vertically-movable clamping member, a cam for operating said clamping member, a pivoted clamping member, a pivoted support for said clamping member, a cam adapted to move said pivoted support on its pivotal connections, a link attached to said pivoted clamping member and a cam engaging with said link, whereby said clamping member will be moved independently of its pivoted support, substantially as and for the purpose specified.
25. In a machine as described, the combination with article-wrapping devices, of a hopper, a pivoted member, a finger normally projecting into said hopper and located on said pivoted member, means for advancing said pivoted member while said finger engages an article within the hopper, means for moving said pivoted member on its pivotal connection to depress said member at the forward limit of its movement, and means to retract said pivoted member while in its depressed position, substantially as specified.
26. In a machine as described, the combination with article-wrapping mechanism, of article-feeding mechanism comprising a hopper, a movable article-retaining member in said hopper, a reciprocatory ejector member intermittently protruding into said hopper, means for advancing said ejector member in an elevated position, and means for retracting said ejector member in a depressed position, substantially as specified.
27. In a machine as described, the combination of article and wrapper feeding devices, article-wrapping devices, and article-clamping devices, of a hopper to hold the articles to be wrapped, a projecting finger on one of said clamping devices whereby single articles will be ejected from said hopper, substantially as and for the purpose specified.
28. In a machine as described, means for feeding an article to be wrapped, means for feeding predetermined lengths of wrapper material, means to form the wrapper in a tube about the article to be wrapped, holding means for the middle portion of said tube and inclosed article means for rotating the opposite ends of said tube, substantially as specified.
29. In a machine as described, the combination with article-feeding and wrapper-feeding devices, of wrapping mechanism, means for holding the article and wrapper stationary, after the wrapping operation, and means for twisting both ends of said wrapper.

while the wrapper and article are being held stationary.

30. In a machine as described, the combination with article feeding and wrapping mechanism, of supporting means for a continuous web of wrapper material, means for feeding predetermined lengths of wrapper material, a pivoted wrapper-cutting knife, angularly-arranged cutting edges on said knife, actuating means for said knife, whereby the wrapper will be punctured and cut simultaneously in two directions, substantially as specified.

31. In a machine as described, the combination with article feeding, wrapping and twisting mechanism, supporting means for a continuous web of wrapper material, means for feeding predetermined lengths of wrapper material, a wrapper-cutting knife for severing such predetermined lengths of wrapper material, a stationary support and a movable support for the wrapper material during the severing process, substantially as specified.

32. In a machine as described, the combination with wrapper and article feeding mechanism, of wrapper-gripping devices arranged on opposite sides of the article to be wrapped, actuating means for intermittently rotating said wrapper-gripping devices, and clamping devices intermediate of said wrapper-gripping devices adapted to hold stationary the article during a portion of the rotation of said wrapper-gripping devices, substantially as and for the purpose specified.

33. In an article-wrapping machine, wrapper-feeding mechanism, article-feeding mechanism, rotary wrapping mechanism to form the wrapper in a tube about the article to be wrapped, article - holding mechanism, and means to continue the rotation of the rotary wrapping mechanism whereby the opposite ends of said tube will be twisted in the same direction, substantially as specified.

34. In an article-wrapping machine, a wrapper-feeding mechanism, means for forming the wrapper into a tube, means for holding a portion of said tube, means for twisting

the other portion of said tube by the continued rotation of the tube-forming mechanism while the first-mentioned portion is being held, substantially as and for the purpose specified.

35. In a wrapping-machine, wrapper-feeding devices, wrapper-gripping devices, means for advancing the forward edge of the wrapper in a circular path about the article to be wrapped by rotating said wrapper-gripping devices, and means for twisting the opposite ends of the wrapper by a continued rotation of said wrapper-gripping devices, substantially as specified.

36. In a machine as described, wrapper-feeding devices, a rotary shaft, wrapper-gripping fingers thereon, means to rotate said shaft and fingers to carry the forward edge of the wrapper about the article to be wrapped, and means to twist the end of the wrapper by the continued rotation of said shaft and fingers, substantially as specified.

37. In a machine as described, wrapper-feeding devices, article -wrapping mechanism, and means for twisting the wrapper ends on opposite sides of the article to be wrapped by a continued rotation of said article-wrapping mechanism, substantially as specified.

38. In a machine as described, the combination with wrapper and article feeding mechanism, of rotary article-wrapping mechanism engaging the wrapper on opposite sides of the article to be wrapped, actuating devices for rotating said wrapping mechanism, holding devices for the article to be wrapped, and means for moving said holding devices into engagement with the article during a portion of the period of rotation of the wrapping devices, substantially as and for the purpose specified.

In testimony whereof I have hereunto set my hand this 21st day of May, A. D. 1904.

JOHN PFEIFER.
